LAUNDRY APPARATUS FOR WASHING AND CENTRIFUGING CLOTHES

Taylor P. Calhoun, Fall River, Mass.; Ann E. Calhoun administratrix of said Taylor P. Calhoun, deceased

Application March 7, 1945, Serial No. 581,513

15 Claims. (Cl. 68—25)

1 This invention relates to laundry apparatus and more particularly to washing and extracting apparatus in which the clothes are first cleansed with a fluid while held in a slowly moving basket, after which the basket is revolved at a high speed to separate the cleansing fluid from the clothes by centrifugal force.

It has heretofore been customary in commercial laundries for the clothes to be washed in one machine and then transferred to a centrifuge for extracting the cleaning fluid therefrom. A standard washing apparatus has comprised a barrel mounted to rotate or to oscillate about a horizontal axis; and a satisfactory type of centrifuge has comprised a basket rotated at high speed about a vertical axis. The use of two separate pieces of apparatus for domestic use, or even in various commercial laundry and cleaning establishments, involves various problems inherent in transferring the clothes from one apparatus to the other, and the operations cannot be accomplished automatically. It has therefore been proposed to combine the two in a single apparatus in which a basket carrying the clothes is first rotated about a horizontal axis for the washing operation, after which the basket is rotated about a vertical axis for the centrifugal extracting of the fluid in the clothes. In such proposed double axis apparatus, the power is applied through transmission gearing, clutches and other devices which require making and breaking mechanical connections before the basket movement can be changed from one axis to the other; and many problems are involved in adapting such a machine for an automatic operation through a complete washing, rinsing, centrifuge cycle.

Other types of combination apparatus have involved rotating the basket about the same horizontal or obliquely inclined axis for both the washing and centrifuge operations; but the centrifugal force set up by a high speed whirling of an unbalanced mass of clothes produces a high stress which causes an undesired pounding or vibration, and this may damage the machine or even pull it from its fastenings. Attempts at compensating for this out of balance condition in a single axis machine have not been wholly satisfactory. Moreover, no attempt has been made to compensate for any out of balance condition involved in the unequal distribution of the clothes in a machine in which the basket is rotated slowly about a horizontal axis for washing and rapidly about a vertical axis for centrifuging. Nor has any way been suggested for

2 applying power to rotate selectively about two different axes a basket that is universally mounted to seek a running balance or to reduce or eliminate vibration.

A primary object of this invention is to overcome such problems and to provide a double axis machine in which the clothes basket may be rotatively moved either continuously or oscillatively about one axis, and preferably a horizontal axis, for the cleansing operation, and thereafter rotated rapidly about a different and substantially vertical axis for the centrifuge operation, and wherein compensation, either partial or full, is made for any out of balance condition of the basket and its contents during the high speed rotation.

A further object of the invention is to provide laundry apparatus having the basket rotatively moved respectively about substantially horizontal and vertical axes for the washing and centrifuging operations, which is so constructed that the basket is substantially universally mounted and it may float during high speed rotation about a substantially vertical axis to provide a running balance and thus compensate for an unequal distribution of the clothes in the basket, and thus provide a smoothly operating machine which will give a long life of satisfactory service.

Another object is to provide a construction which permits the loaded basket to attain a static balance at the end of the washing operation and then lock it in that position for the centrifuging stage.

Another object of the invention is to provide laundry apparatus having two independently controlled power driving mechanisms for rotatively moving the basket slowly about a horizontal axis in an initial cleansing operation and then rotating it rapidly about a vertical axis for the centrifugal extracting step, and which will accelerate and decelerate the basket movement smoothly.

A further object of the invention is to provide a laundry apparatus in which the clothes basket is moved about two different axes for the washing and centrifuging operations, and wherein the power drives for the two movements are maintained always in an operative relationship with the basket, so that each may be selectively employed for moving the basket without the disadvantages involved in making and breaking mechanical drive connections, and the various stages of washing, rinsing and centrifuging may be readily accomplished merely by suitable control of the power to the two drives, as well as the in-

introduction and removal of the cleansing and rinsing fluids.

A further object of the invention is to provide a laundry apparatus having the clothes basket rotatable about two different axes for the washing and extracting operations in which the basket is universally or otherwise so mounted that it will never be out of balance or, the nature of the balance being disturbed by movement of the clothing or any other influence affecting the location of the center of gravity, will tend to compensate automatically for such out of balance condition by moving to restore its center of mass into alignment with the axis of rotation, and wherein power driving mechanism is maintained in operative relationship with the basket and may be applied for rotative movement of the basket irrespective of the position which the basket has assumed in seeking to compensate for an out of balance condition.

A further object of the invention is to provide a construction having a double axis suspension for the clothes basket which permits cleansing or rinsing fluid to be introduced to the interior of the basket during its rotation about either of said axes.

Another object is to provide for oscillation of the basket for a washing operation and continuous rotation for centrifuging. Other objects will be made apparent or pointed out in the following disclosure.

Although the various principles and aspects of my invention herein described may be applied separately or in various combinations in many types of apparatus, I have illustrated in the drawings certain preferred embodiments having them in combination. The preferred laundry apparatus has a basket mounted for oscillative or rotative movement about one axis, and preferably a horizontal axis, for the cleansing operation and further mounted for rotation about a substantially vertical axis for centrifugally extracting the fluid therein. The basket is so flexibly or universally mounted that, in accordance with the laws of motion, it will move laterally to bring the center of mass into alignment with the axis of high speed rotation and so seek and preserve a static balance at the beginning of the centrifuge stage or maintain a running balance during high speed rotation about a vertical axis.

The support for the clothes filled basket may comprise a universal joint carrying the basket as a depending or an inverted pendulum with the parts so arranged that the basket may swing automatically to permit its center of mass to seek axial alignment with the center of the universal suspension joint. The basket may also be supported on gimbal rings or flexible or resilient supports or other suitable constructions which permit the center of mass of the basket and its contents to move towards a position of static or running balance. Power may be applied selectively to rotate the basket either continuously or oscillatively about one axis for the cleaning operation or to rotate it continuously about the vertical axis for the centrifugal extraction of fluid by means of drive mechanisms which are maintained in operative relationship with the basket for all positions thereof. Although the power drive may be an electric motor, I prefer to employ a motor operated by fluid under pressure and particularly for moving the basket during the washing operation. For example, the fluid propulsion for rotating the

basket about either a substantially horizontal axis or a vertical axis or both may comprise a pelton wheel drive. This type of flexible drive may also be employed for rotating the basket about either or both axes in double axis laundry apparatus having no compensation for providing a running balance. The fluid jet pelton wheel drive is preferred since it may be maintained in an operative relationship with the basket, so that control of the basket movement requires merely a manual or automatic control of suitable valve mechanisms.

The application of these various principles of my invention to different and preferred types of laundry apparatus is shown in the accompanying drawings, and in which:

Fig. 1 is a vertical elevation, partly in section, showing one form of construction in which the clothes basket is revolved about both horizontal and vertical axes by means of pelton wheel drives, and wherein the basket is so suspended that it may seek a running balance during centrifuging and so compensate for an out of balance arrangement of the clothes;

Fig. 9 is a fragmentary detail showing how the basket is rotatively oscillated; and

Fig. 10 is a fragmentary detail showing an automatically operated lock for the statically balanced basket.

Referring first to the construction shown in Figs. 1 to 4 inclusive, clothes may be washed or cleaned in a suitable fluid, such as a solution of soap and water or a dry cleaning fluid, such as gasoline or benzine, by oscillating or tumbling them in a basket which moves, and preferably rotates, about a horizontal axis. In this construction, the basket 10 is shown as substantially spherical in shape, although other shapes may be employed. This basket is preferably made of sheet metal provided with a large number of suitably located, close spaced perforations 11 so arranged that the cleaning fluid may pass between and through the clothes in the basket.

For tumbling the clothes, a set of baffles or ribs 12 may be provided. These may be formed by crimping the walls of the spherical basket in the process of manufacture, or as illustrated in Fig. 2 this may comprise a V shaped solid or perforated rib that is welded or otherwise secured in place. Each of the ribs, of which there may be four, may extend inwardly to a considerable distance, such as about one-third of the radius. The ribs may be arranged as desired, such as cross-ways of the basket with their inner edges paral-

lel with the axis of the basket, so that when rotated about a horizontal axis the clothes will be carried upwardly until they slide off the ribs and thus are tumbled through the cleaning fluid within the basket. If desired, the basket may have a central vertical partition perpendicular to its axis of rotation. This divides the clothes so that the wet mass is less subject to tearing strains during centrifuging, as may be set up by the centrifugal force pulling the clothes in opposite directions across the vertical axis.

In order to permit rotation of the basket about a horizontal axis, it is provided with trunnions 15 in axial alignment which are mounted in radial and end thrust ball bearings 16 of suitable construction. The outer bearing raceway is carried within the inner cylindrical surface of a bearing sleeve 17 supported by a ring 18 that is mounted on the depending arms of a yoke shaped gimbal frame 20, as illustrated.

The gimbal frame 20, which may be made of tubes or flanged sheet metal, may comprise a set of U-shaped arms (Fig. 2) extending radially from an upper connecting point and joined at peripherally spaced locations to the ring 18. These arms are mounted for rotation about a vertical axis on a ball and socket joint which supports the gimbal frame at its top and permits such rotation as well as a limited universal movement. The joint comprises a ring shaped socket plate 24 mounted on a cross bar or plate 25 near the top of the machine. The plate 24 is provided with a partial spherical concave surface to form a socket which is arranged to support the so-called ball 26 which is also shaped as an annular plate having a partial spherical convex surface fitted in the socket. This ball member 26 has a central opening therein within which is fitted a flanged sleeve 27. A flanged cover plate 28 rests on top of the horizontal flange of the sleeve 27 and keeps foreign matter out of the joint. A nut 29 is threaded on the reduced end of a hollow post 30 passing through the ball and socket joint. This is welded to the top central portions of the arms of the gimbal frame 20. Thus, the gimbal frame is supported by the ball and socket joint for rotation about a substantially vertical axis and a pendulum oscillation about the center point of the pivot.

Suspended from and secured to the vertical equatorial ring 18 are frame members 32 (Fig. 1) which may be radially arranged like the yoke arms 20. A trunnion 33 projects downwardly from the frame 32 in axial alignment with the ball and socket joint 24, 26 which supports the gimbal frame 20. This trunnion 33, which is integral with frame 32, is mounted in a suitable bearing, shown diagrammatically as a cylindrical sleeve 34 keyed in a cylindrical socket in the shoe 35. This shoe has its lower surface 36 shaped as part of a sphere whose center is the center of the ball and socket joint that aids in swingingly supporting the gimbal frame. That convex surface 36 is mounted for sliding movement in any radial direction on a concave partial spherical surface on the top of a plate 37 that is suitably carried on the partition 38 of the machine. This support at the bottom of the basket may be omitted. This construction provides for a universal lateral movement of the basket, i. e. movement in all directions of the compass. It permits the basket to assume a pendular motion of revolution in response to the forces acting thereon and thus to align its center of mass with the axis of rotation and compensate for a normal out of balance con-

dition that may arise from an uneven distribution of clothes. Access to the basket may be had through one or more suitably located lockable hinged or sliding doors 42 which may be brought into alignment with an opening in the outer casting normally closed by a door 43.

A primary feature of this invention involves the propulsion of a basket which is arranged for rotative movement about two axes by means of driving mechanism that remains in operative relationship with the basket at all times and so does not require the throwing of clutches to connect and disconnect the power. For this purpose, I preferably employ two separate motors or driving mechanisms which are so mounted and arranged that it is merely necessary to turn on and off the power, such as an electric current controlled by a switch or fluid pressure in a line controlled by a valve. Although this phase of my invention is applicable to rotating a double axis basket in apparatus which provides no compensation for an out of balance condition, yet it is particularly useful in apparatus of the type herein described which provides such compensation, since the power drive will operate at all times for any static, rotative or dynamic position of the basket. I prefer to employ a fluid drive which propels the basket in one or both rotative directions. I may use various types of hydraulic or fluid pressure apparatus, such as a turbine or a water wheel or other vane types of drive mechanisms, or an hydraulic coupling in a mechanical drive, which are suitable for propulsion by means of liquid or gas under pressure. I prefer to employ a pelton wheel operated by a jet of fluid, and preferably the cleaning fluid itself, driven by a suitable pump.

As shown in the drawings, the pelton wheel employed for rotating the basket about a horizontal axis within the bearings 16 comprises a set of pelton buckets 45 projecting radially from an equatorial portion of the basket or which are otherwise suitably located. These blades or buckets 45 may be of suitable shape, such as the two shallow, slightly concave plates meeting at a central divided edge, as shown at the bottom of the basket in Fig. 1. These buckets may be suitably welded or otherwise fastened to a band 46 affixed vertically to the control or equatorial portion of the basket. A jet of liquid or gas may be forced under pressure against the buckets from a suitable supply pipe. This comprises a nozzle 48 projecting substantially horizontally from the lower end of an elbow 49 which is threaded into the hollow opening of the suspension post 30 that carries the gimbal frame. A stationary flexible pipe 50 is suitably connected to the nozzle through a coupling (not shown) which permits rotation of the post 30. The pipe 50 may receive fluid under pressure from a desired source, such as a tap connected with the house main.

The basket 10 may be rotated about the suspension axis of the ball and socket joint by a pelton wheel suitably located on the basket or the gimbal frame. In the construction shown, the ring 18, which carries the horizontal bearings 16, has a set of pelton blades or buckets 54 suitably secured on its outer periphery in proper spacing for rotating the basket at a high speed about a substantially vertical axis. A nozzle 55 is arranged to direct a jet of fluid under high pressure against these blades 54 and thus rotate the basket at a rate determined by the volume and pressure of the fluid. The jet is connected

through a pipe 56 with a suitable source of fluid pressure.

Although the pipes 50 and 56 may receive fluid under pressure from other sources, such as a tap from the municipal water system, I prefer to employ a self-contained fluid pressure system in which the cleansing fluid is forced under pressure to propel the pelton wheels. In this construction, the outside fluid container or casing 60, which carries the basket structure, may be 5 shaped as a hollow body of rectangular or cylindrical cross section. The lower plate 38, together with the adjacent walls of the casing and a partition 61 form an enclosure for an electric pump unit arranged to propel fluid through the pipes 50 and 56. The water or other cleaning fluid may be introduced into the casing through a 10 valved pipe line 62 shown at the top right hand corner of Fig. 1. In a normal washing or bath rinsing operation of the device, the level of the cleaning fluid will be such that the perforated basket 10 is about a third filled. A sight glass 63 may be located within a rectangular slot in the casing wall so as to show the height of the fluid, and a valved overflow pipe 64 may also be provided to determine the fluid level. The fluid passes downwardly through a passage 65 in the wall 38 and fills the sump 66 or settling basin at the right of the pump casing.

The pump unit comprises an electric motor 67, or other suitable source of motive power, which drives the propeller of a suitable centrifugal pump 68 axially aligned with the connected to the shaft of the motor. The pump receives cleansing fluid from the sump 66 through a central pipe 69 connected with an opening in the partition 61. The fluid is driven centrifugally by the pump through the connection pipe 70 into a valve casing 71 which is arranged to control the flow of the fluid to the two pelton wheels as well as the removal of the cleaning fluid from the washing zone.

The valve, which may be of suitable construction, comprises a rotary cylindrical or disk shaped member 72 (Figs. 2 and 3) provided with a horizontal passage 73 subtending an arc of 90° and adapted to connect the pump line 70 with the pipe line 50 when the rotary valve is in the position of Fig. 2. This connection is made through two of three holes spaced by 90° in the outer cylindrical wall 74 within which the valve part 72 rotates. When the valve 72 is rotated through 90° to the position of Fig. 3, then the pump line 70 is connected with the pipe 56 which causes a jet to strike the buckets 54 and whirl the gimbal frame and the basket carried thereby about the axis of the ball and socket joint.

The rotary valve disk 72 is keyed to an operating shaft 76 (Fig. 1) passing therethrough, and this shaft extends upwardly to a position out of the path of the revolving gimbal frame and basket where it may be operated by means of a bevelled gear 77 on the shaft meshing with a gear 78 keyed on a cross shaft suitably mounted on the machine and which is operated by a handle 79 arranged on the outside of the casing 60. The lower end of the shaft 76 connects with a further rotary disk shaped valve plate 80 (Figs. 1 and 4) in a valve casing 81 resting on the bottom wall of the washer. The casing 81 is provided with an opening 83 close to the casing floor which gives access to the fluid within the sump 66. The rotary plate 80 has a passage 82 subtending an arc of 90° and arranged to connect the hole 83 with a valved drain pipe 84

which empties into the sewer or other outside pipe line for removal of the fluid from the washing machine. The upper valve disk 72 also has a vertical hole 86 (Figs. 2 and 3) adapted to connect an opening 87 in the partition 38 with a drain pipe 88 which is so located above the valve structure that the cleaning fluid may be drained down to the level 89 (Fig. 1).

These various valve parts are so arranged that when the handle 79 is thrown to one position the pump may send fluid under pressure through pipe 50 (Fig. 2) to the pelton wheel buckets 45 which causes the basket to revolve about a horizontal axis and tumble the clothes through the cleaning fluid contained within the casing. The other valve passages are closed at that time. When the upper valve is moved to the position of Fig. 3, the vertical hole 86 through the upper valve disk 72 connects with the drain pipe 88 and the fluid drains off until it reaches the level 89 below the basket. At the same time, the pump 66 is connected with the centrifuge propulsion system comprising the jet 55 and the pelton buckets 54 on the gimbal frame 20, and thus 25 starts rotation of the frame 20 which ultimately whirls the basket at the high speed required to dry the clothes. The clothes may be rinsed repeatedly by simply whirling out the old cleaning fluid and then introducing fresh fluid through pipe 62 while the valves are in the positions of Fig. 1 for tumbling the clothes. When the machine is to be entirely emptied, the handle 79 is thrown to a further position at which the lower valve 80 permits the fluid to pass through the exit pipe 84. This lower valve remains closed 30 during both the washing and the centrifuging of the clothes, so that the sump always contains fluid for operation of the pump.

It will thus be seen that the cleaning fluid, 40 such as an aqueous soap solution, will serve to operate the pelton wheel for tumbling the clothes while the outer casing is filled with water at the required level. Also, the rinsing water serves the same purpose. When the clothes are to be 45 centrifuged, enough of the last rinse water remains in the sump to operate the high speed pelton wheel 54. It may also be noted that centrifugal force prevents the clothes from being wetted by water splashing from the pelton buckets 54, so that the fluid will be adequately extracted.

In the construction of Figs. 5 and 6, I have shown a preferred form of the invention in which the basket carrying the clothes is universally mounted for automatic compensation of any out 55 of balance condition that arises at the start of the centrifugal extracting of the fluid. In this construction, the basket 100 is mounted on two pivotally connected gimbal frames 101 and 102 arranged for rotative motion about two axes at right angles to each other.

The basket may be spherical in shape or otherwise suitably shaped. If desired, the basket may have a central partition so arranged that the clothes may be roughly divided into two equal 65 portions when first put into the machine. A suitable door 103 on the basket and a communicating door 104 on the outer casing are provided for introducing the clothes. The basket may be 70 formed of perforated sheet metal suitably shaped and crimped to provide the clothes tumbling ribs or paddles 105.

At diametrically opposite points on a horizontal equator (Fig. 6) are two trunnions or bosses 106 secured to the basket. The gimbal frame 101 is

substantially a circular ring and made either of a flat band or tubular metal, such as rustless steel. This ring is likewise provided with two bosses 108 diametrically opposed to the bosses 106 of the basket, and pins 109 passing through the two sets of bosses form bearings for the basket within this gimbal frame 101. Any other suitable bearing construction may be provided.

The gimbal ring 101 is likewise pivotally secured to the depending arms of the semi-circular yoke frame 102. At the right hand side of the yoke, a bearing pin 110 secured to and projecting radially from the inner ring 101 projects into and rotates within a suitably shaped bearing hole 111 in the outer frame 102. At the left hand side, a special bearing structure is provided as will be described, and the parts are so arranged that the inner ring is mounted for rotation about axially aligned bearings lying in a horizontal plane. If desired, suitable ball or roller bearings may be provided to insure a better bearing support for the parts. Thus the basket may rotate freely to move the center of mass laterally into alignment with the center of the basket and so seek a static balance as determined by uneven distribution of the clothes therein.

In order to provide for centrifuging the clothes, the yoke shaped frame 102 is mounted for rotation about the substantially vertical axis of a central post 114 suitably secured to or integral with the yoke frame 102 midway between and at right angles to the bearings which carry the inner gimbal ring. The post projects upwardly through the top wall of the casing 115, which is provided with an enlarged boss 116 to give an adequate radial bearing support for the post 114. Suitable thrust roller or ball bearings 117 surround the post 114, and the lower raceway of the bearings rests on the boss 116 while the upper raceway is held in place by a washer and nut 118 threaded on the end of the post. Thus the entire weight of the clothes basket and the supporting frames is borne by the thrust bearings 117 and the frame 102 may be rotated about that vertical axis to extract the fluid in the clothes.

The container for the water or other cleaning fluid may be shaped to provide a partial spherical wall 120 located beneath and fairly close to the basket 100 but giving enough clearance so that the gimbal ring 101 may revolve freely. A vertical tubular wall 121 below the basket forms a sump 122 connected with the washing space and which provides a fluid supply for the pump. The cleaning fluid, such as soap and water, may be admitted through a valved pipe 123 suitably located and connected to a supply, such as the house water main.

The basket and its supporting frame may be rotated rapidly about a vertical axis by means of a pelton wheel 125 secured to the gimbal yoke frame 102 and surrounding the post 114. This wheel may be arranged equatorially of the basket or otherwise as desired. The blades 126 of the pelton wheel are struck by a fluid jet from the nozzle 127 of a pipe 128 controlled by a valve 129. The fluid under pressure is suitably derived, such as from a centrifugal vane pump 130 located outside of and near the sump 122 and which is connected through the pipe line 131 with the nozzle pipe 128. The centrifugal pump 130 may be of desired construction, and it is driven by a suitable variable or constant speed electric motor 132 having its shaft axially connected to the shaft of the centrifugal propeller. The fluid is derived from the settling tank 122 through a passage 133

connecting with the central portion of the pump. The pelton wheel 125 and its vanes, as well as the other pelton wheels described, will be of suitable size and shape, and the velocity and the volume of the jet of propelling fluid will be proportioned in accordance with the desired end.

This type of drive is one in which the pelton wheel will accelerate smoothly to the required rotative speed and thus will not impose any severe strain on the machine parts or the clothes within the basket. The basket may be revolved for the tumbling and washing operation by means of a second pelton wheel having its buckets 135 secured to and projecting substantially radially from a steel ring 136 arranged equatorially around the basket with reference to the axles 109.

If desired, a pair of stop pins 137 may be adjustably threaded through threaded nuts secured to opposite sides of one of the yoke arms 102 and so positioned that the equatorial gimbal ring 101 may swing only through a suitable limited angle, such as 10 or 20 degrees, and thus insure that the basket axle pins 109 will remain substantially horizontal during the slow speed clothes tumbling stage. Various other expedients may be employed for this purpose. Also, the stops may be located on a yoke arm arranged at 90° to the two arms 102 so as to provide stops adjacent to the pins 109 on the gimbal ring. In the construction illustrated, the stops are arranged at such angles and sufficiently far from the gimbal pins 111 so as to engage the ring 101 at a considerable distance from the pivots. This construction permits locating the container wall 120 close to the basket, and if desired that wall may serve as the stop limit.

The normal out of balance condition will usually require only a limited rotation of the ring 101, so that the stops 137 will not materially hinder the automatic compensation for running balance, which is attained by free rotation of the basket and the gimbal ring to move the center of mass laterally into alignment with the vertical axis of rotation.

In order that a fluid jet may strike the buckets 135 for any position of the gimbal ring 101, I propose to introduce the fluid through the gimbal ring itself, and thus have this jet always correctly positioned when the gimbal ring turns to correct an out of balance condition. The inner gimbal frame 101 may be provided, as shown at the left hand portion of Fig. 5, with a large cylindrical opening which receives and forms a bearing for the short trunnion 138 projecting inwardly from the end of the left hand arm of the gimbal yoke frame 102. This trunnion 138 has a central opening 139 connecting with a passage 140 within the yoke arm 102. The horizontal passage 139 connects through a short branch with an annular groove 142 on the outside of the trunnion 138, and this groove serves to supply fluid to the nozzle hole 143 in the gimbal ring 101 which points always towards the buckets 135 irrespective of any swinging movement of the ring about the trunnion. The passage 140 in the gimbal yoke 101 connects at its upper end with a vertical passage 144 within the bearing post 114 and which in turn receives fluid from a supply pipe 145 through a joint (not shown) which permits rotation of the post 114. The supply pipe may branch off the main pipe 131 and thus receive fluid under pressure from the pump. A valve 146 in the supply pipe 145 controls the flow of fluid to the pelton blades 135.

Thus, by control of the two valves 129 and 146,

11

the basket may be revolved at a desired rate for tumbling and washing the clothes, or it may be revolved about the vertical axis of the gimbal supporting post 114 to throw out the cleansing fluid centrifugally in a high speed whirling operation. The sump 122 has two exit pipes 147 and 148 suitably controlled by valves and connecting with an outside drain pipe. All of the fluid may be drained from the machine through pipe 148; but the pipe 147 is located above the intake 133 to the centrifugal pump so that fluid is always provided for the pump operation during the centrifugal extraction. The various valves and pump driving mechanism may be suitably controlled by a timing control device, so that the various stages of washing, rinsing and centrifuging the clothes may be successively accomplished without attention on the part of the operator. The valves 128 and 146 or other adjustment devices may be so adjusted preliminarily as to control the volume of the jets which revolve the basket in the two directions. A comparatively slow speed such as 30 R. P. M. will serve the purpose of tumbling the clothes through the cleansing fluid, and a speed of 300 R. P. M. will extract the fluid from the clothes.

In Figs. 7 and 8 I have shown another modification of this invention wherein the clothes basket is mounted for a universal lateral movement of the center of mass, so that it may seek automatic compensation for an out of balance condition of the clothes in the basket. I further provide for spraying or introducing fluid into the clothes during washing or rinsing thereof or while centrifugally removing fluid therefrom. This construction comprises a spherical clothes basket 150 made of metal having perforations suitably arranged for the admission of fluid from the surrounding container, and which may have a vertical diametrical partition 151 therein as well as the doors 152 communicable with a door in the casing for the necessary access to the interior thereof. If desired, ribs 153 may be suitably arranged for dragging the clothes through the wash water and causing the tumbling and washing action. This basket is supported by trunnions 154 diametrically arranged in a substantially horizontal position and which are carried by suitable bearings, such as ball bearings mounted in raceways 155. These raceways are resiliently supported, as will be explained, in the two depending arms 156 of a yoke frame which may be mounted substantially the same as the yoke frame shown in Fig. 5. That is, the yoke frame is secured integrally to a vertical flanged post 158 which is mounted in a radial bearing sleeve 159. The post and the basket are supported on a suitable thrust bearing 160, shown for simplicity of illustration as balls between the two raceway plates. A nut 161 threaded on the top end of the post holds the parts in position. The yoke arms 156 and the basket supported thereby may be revolved by means of a suitable variable or constant speed fluid pressure or electric motor. In the form illustrated, an electric motor 162 is mounted on the top of the casing 163. The motor 162 is connected by a V-belt drive to a pulley 164 keyed to the post 158, so that the basket may be rotated about the vertical axis of the post at a required speed for the centrifugal extraction of fluid from the clothes. A flange 165 on the bottom of the post 158 prevents upward movement of the assembled parts.

Compensation for an out of balance condition due to uneven distribution of the clothes in the

12

basket at the beginning of the high speed centrifuge action is obtained by so mounting the bearings for the horizontal trunnions 154 that they move up or down under a resilient restraint as the center of mass seeks to move laterally and align itself vertically with the axis of rotation. To this end, each of the yoke arms 156, which may be made of tubing or other suitable construction, has its lower end constructed like a piece of cylindrical tubing 170 but which is so bent that the center line of the tubing is an arc of a sphere centered at the center of the basket 150. The walls of the tubular portion 170 are closed at the bottom 171 and the top 172. Two elliptical openings 173 having their longer dimensions vertical are formed medially at opposite sides of this arcuate tubular part 170, and they are so arranged that the trunnion 154 of the basket may project therethrough and be permitted a necessary vertical movement. The trunnions rotate on the radial and end thrust bearings 155, the inner raceway of which is held in place by a shoulder on the trunnion and a nut 175 threaded thereon.

The outer raceway of each ball bearing is resiliently supported between two coiled compression springs 176 and 177. The upper spring engages the top wall 172 of the recess within the arcuate tubular portion 170, and the lower end of the spring rests against the inner end of a shoe formed of a piece of tubing 178 closed at its lower end and shaped to fit slidably within the arcuate recess of the outer tubing 170. The lower side of that slide shoe interfits with and so positions the outer raceway of the ball bearing 155. Similarly, at the lower portion of the arcuate tubing 170, the compression spring 177 engages the bottom 171 of the tubing, which may be a screw cap, and the upper end of that compression spring likewise fits within the recess and engages the upper end of a tubular slide shoe 179, similar to the part 178, which slides within the outer tubing 170. The shoe engages the under side of the outer raceway of the ball bearings.

Hence, the spherical basket 150 is so mounted that the trunnions may move vertically by revolving under resilient restraint about the center of the sphere. That is, when one trunnion moves downwardly, the other trunnion moves upwardly to an equal extent as permitted by the slide shoes 178 and 179 which can move only in an arcuate path defined by an imaginary sphere centering at the basket center.

The two lower springs 177 are made sufficiently strong to carry the normal weight of the loaded basket; but the basket cannot move downwardly except to a very limited extent as permitted by the looseness or play of the slide shoes 178 and 179 in the arcuate tubing 170. That is, if the weight is such that both trunnions 154 attempt to move downwardly to an equal extent at the same time, the lower slide shoes 179 will bind against the outer portions of the interior face of the tube 170 and the upper slide shoes 178 will likewise bind against the inner portions of their slide recesses. On the other hand, the shoes may move freely just so long as the trunnions are aligned diametrically with the center of the imaginary sphere defined by the arcuate center lines of the recesses. Hence, if the clothes in the basket are unevenly distributed so that the center of mass is not vertically aligned with the center of the sphere, the basket will rotate freely about its horizontal axis and compensate in part for the out of balance. If the center of mass then re-

mains at one side of a vertical plane through the basket center, then when the basket is rotated at high speed for the centrifuging operation, that center of mass will move laterally into vertical alignment with its axis of rotation to that extent permitted by the spring mounts, in which case one trunnion will move down and the other trunnion moves up to an equal extent. The length of the springs and the arcuate recess, as well as the elliptical openings 173 are made of sufficient size so that the normal out of balance condition may be adequately compensated. This construction, like the others, provides for a universal lateral movement, i. e. relative to the directions of the compass, so that the center of mass may align itself with the axis of high speed rotation.

The basket is rotated for the washing or cleansing operation by a flexible power drive which will operate satisfactorily for any position of the basket. This preferably comprises a pelton wheel construction of the type above described. The pelton wheel may be suitably located, such for example as equatorially and vertically of the sphere, as illustrated in Fig. 7. This wheel comprises the pelton blades 180 integrally secured to a band 181 that is in turn affixed to the outer surface of the perforated spherical basket. Fluid under pressure is supplied from a nozzle 182 which is so directed that the fluid will normally strike a dividing edge between the concave bucket portions of the blade made in accordance with standard construction. Fluid under pressure is suitably supplied to the nozzle 182 through a pipe 183 connected with a source of pressure, such as a pump of the type above described with reference to the constructions of Figs. 1 and 5 and which is suitably operated either by a separate motor or by a shaft extending downwardly from the motor 162. This pipe 183 threads into an elbow opening in a stationary cap 184 of suitable water tight construction which closes the upper end of a central recess 185 in the post 158. A pipe extension 186 connects with the cap and is disposed centrally of the recess in the post and at its lower end it connects with a pipe 188 which is suitably mounted in the lower end of the post so that the pipe may rotate about its axis and thus permit the nozzle 182 to swing laterally as required. The pipe 188 is arranged vertically, while the nozzle extends downwardly and laterally as illustrated in Fig. 8 so that the fluid under pressure will be directed against the buckets 180.

Since the basket sphere 150 may tilt toward either side, I have provided a construction which causes the nozzle to follow that tilting operation. A simple device for this purpose comprises a U-shaped ring 190 having spaced parallel flanges engaging a follower ball 192 depending from the lower end of an arm 193 which projects laterally from and is secured to the nozzle 182. The nozzle 182 projects from and opens into a hollow cylindrical valve like sleeve 194 (Fig. 8) provided with closed ends. The sleeve 194 is rotatably mounted within a cylindrical casing 195 that is formed as an extension of the pipe 188. A suitable hole 196 in the inner sleeve 194 and which is larger than the opening at the bottom of the pipe permits the nozzle to raise and lower slightly and yet supply the full flow of fluid thereto. This particular construction is required to permit the spherical basket to tilt upwardly or downwardly at either side and thus require raising the nozzle somewhat as well as swinging it laterally so that it will follow in an approximately correct

position for throwing the fluid against the pelton blades.

A further feature of this invention involves introducing fluid into the interior of a double axis basket during either the washing or the centrifuge operation, and whether or not compensation is made for an out of balance condition. If clothes are being cleaned with gasoline or benzine, it may be desirable to recirculate the fluid or to introduce new fluid through the basket during that operation. Also, an aqueous soap solution or other cleansing fluid may be introduced into the basket for laundering operations. It is particularly useful to introduce clear water under a desired pressure for a pelting rinsing operation, after the washing fluid has been withdrawn from the casing 163.

For these various purposes, I have provided an opening 200 through each of the trunnions 154 which communicates with the interior of the spherical basket, and this opening serves for the introduction of the desired fluid for any position of the basket and whether it is rotating about the trunnions or is being rotated about the vertical axis. A pipe 201 communicates with that opening and is suitably connected to the trunnion. This pipe is somewhat L shaped and its upper portion 202 is arcuate shaped and slidably fits within an arcuate shaped end 203 of a pipe 204 that is suitably carried by each of the yoke arms 156. The parts 202 and 203 have a slideable interfitting arrangement which permits the sphere to tilt as required for an out of balance compensation. It will be appreciated that the pipe 201 may be a flexible rubber tube suitably connected to the pipe 204 so as to permit the required tilting of the sphere. The upper end of each pipe 204 communicates with a lateral opening 205 through the lower flanged portion of the post 158, and that opening communicates with the space 185 within the hollow post. This space surrounds and does not communicate with the pipe 186 that supplies the fluid under pressure to the pelton wheel. The cap 184 has an annular passage 207 therein communicating with a supply pipe 208 through which the desired fluid is introduced. The cap is held in a stationary position by the pipes 183 and 208. By this means, I may supply the desired fluid, such as clear rinsing water, while the basket is being revolved about either of its axes. The inner end of the pipe 200 may have a suitable spray nozzle or be otherwise shaped as desired, and by this means water under high pressure may be thrown against the clothes and serve by a pelting action to drive the washing water out of the clothes. If a cleansing medium is forced into the basket, such as a soapy water solution or benzine, then that same pelting action will aid in cleansing the clothes. It will also be understood that the nozzle channel 200 may be extended to a position near the center of the sphere if desired, so that the fluid may be introduced into the central portion of the basket, whereby centrifugal force will tend to throw it outwardly through the clothes and further aid in cleansing them.

It will also be understood that the various constructional details of the other modifications above described, such as shown in Fig. 5, may be employed in connection with the apparatus of Figs. 7 and 8. Also, the constructions of Figs. 1 and 5 may be so modified as to provide for the spray rinse of the clothes within the basket, or for circulating any desired fluid directly into the

interiors of the clothes baskets, either while the basket is stationary or rotating about either axis. This fluid may come from a fresh source or from the settling basin or sump at the bottom of the apparatus. Thus, I may pelt the clothes with a high speed jet or spray of desired fluid. Such a construction involves largely a duplication of the conduits arranged to introduce the pelton jet to the gimbal ring of Fig. 5 and so need not be here illustrated. The structure of Fig. 1 may be made substantially like that shown in Fig. 7 for introducing the extra fluid.

The basket in any of these modifications may be oscillated intermittently through a part turn or several turns in one direction and then in the opposite direction by so arranging jet nozzles that the propelled fluid strikes first one side of a double pelton wheel vane and then on the other side, and for this purpose the vanes may be provided with the standard pelton buckets on both sides thereof. A suitable three-way valve may be manually or automatically controlled to send the fluid first to one nozzle and then to the other for the oscillating motion. For example, the construction shown somewhat diagrammatically in Fig. 9 may be employed, in which the basket 10 of Fig. 1 may have the blades 45 replaced by double sided blades 210 which have the standard pelton buckets on both sides thereof. Two nozzles 211 and 212 face in opposite directions and downwardly toward the blades. The nozzle 211 communicates with a pipe 214 opening to a passage 215 of a suitable three-way valve 216 provided with a handle 217 to align the openings. Similarly, the other nozzle 212 communicates through its pipe extension with an opening 218 in the valve casing when the valve handle is suitably operated. Fluid under pressure enters the valve through the pipe 219. The handle 217 may be operated by suitable timing mechanism or by automatic constructions arranged to permit the basket to oscillate through a part turn or several turns before the valve is thrown to reverse the direction of rotation. Thus the clothes may be tumbled for the washing action by rotative oscillation of the basket about the horizontal axis, and this will aid in preventing the clothes from twisting together. It will, therefore, be appreciated that the term "rotary" and other like expressions as used herein are intended to cover either a continuous motion or an intermittent oscillating rotative motion of the basket about that axis which serves for the washing operation.

As a further feature of this invention, I may add a stop or a locking device which serves automatically to hold the basket in a self-attained static balance at the beginning of the centrifuge high speed rotation. That is, after the clothes have been initially washed by the tumbling operation above described and the wash water has been removed, the basket will automatically seek a static balance insofar as permitted by the particular construction involved. In the construction of Fig. 1, the basket may merely rotate about its horizontal axis, while in the construction of Fig. 5, both the basket and the gimbal ring 101 may move to such a position as to obtain a perfect static balance. The construction of Fig. 7 also permits a limited movement towards a static balance. Since the removal of water during high speed rotation about the vertical axis may change the location of the center of mass, the basket may move to a new position under the forces involved. To avoid such movement during centrifuging, I propose to lock the basket in its assumed static position before the basket is rotated at high speed.

10

A suitable stop and governor device as applied to the construction of Fig. 5 is illustrated in Fig. 10. This comprises a governor weight 220 mounted on the end of the long arm of a lever 221 of the first class which is suitably pivoted on a pin 222 carried by a bifurcated post 223 that is suitably mounted on one of the yoke arms 102. The lever is preferably arranged radially of the spherical basket 100. A stop 225 shaped at its lower side to engage the outer surface of the basket or some other constructional part is mounted on the lower end of a slide rod 226 slidably passing through a suitably located hole in a laterally extending lug 227 on the yoke arm 102. This rod is pivotally connected at its upper end with the short end of the lever 221. The weight 220 is so located, as illustrated, that when the yoke arm 102 is revolved at an increasing speed, the weight 220 moves outwardly under centrifugal force and thus pushes down on the rubber lock 225 and clamps it against the adjacent portion of the basket which has moved into position when the static balance was attained. The lock 225 and its supporting lug 227 are so located and arranged that the basket may rotate and move automatically to obtain a static balance without the pelton blades interfering with the lock. The lug 227 may be made long enough to keep the lock out of the path of the blades for any normal adjusted position thereof. Various other constructional features may be employed for the purpose. Centrifugal force holds the weight in a clamping position during the high speed centrifuge operation, and thus the basket cannot move to any new position until the centrifugal force has decreased enough to permit the weight 220 to fall and release the lock 225 from engagement with the basket. This feature may be similarly applied to the other constructions of Figs. 1 and 7 so as to permit the basket to attain a static balance and then be held from rotation about the horizontal axis during centrifuging.

The operations of these various devices will be apparent in the above disclosure. The construction of Figs. 1 and 2 is such that the clothes basket is supported like a pendulum on a universal ball and socket joint. Gravity holds the basket with its center of mass substantially aligned vertically with the pivot point of the ball and socket joint during the operation of tumbling the clothes about the horizontal axis. However, when the basket is to be rotated about the substantially vertical axis by means of the pelton blades 54, there may be an out of balance condition because of uneven distribution of the clothes in the basket. Consequently, as the centrifuge rotation accelerates, the center of the basket moves automatically in response to the laws of motion until the rapidly revolving center of mass of the basket and clothes, under the influence of gravity and centrifugal force, attains a vertical alignment with the center point of the supporting ball and socket joint, and the geometric center of the rotating basket moves in a circular path about its point of suspension. As the fluid in the clothes is thrown outwardly therefrom, the center of mass may change its position and the basket automatically seeks a new running balance. But the lock 225, if used, will prevent the basket from rolling on its horizontal axis.

In the construction of Figs. 5 and 6, the basket can attain a static balance at any time by merely turning about its two pivotal supports. Thus, when it is started in rotation for the centrifuging

step, that center of mass is in a vertical alignment with the axis of rotation of the suspension pivot 114. The lock 225, if used, will hold it in that assumed position during centrifuging. If the lock 225 is not used, then the basket remains free to move under the various forces involved. In the construction of Fig. 7, the supporting frame for the basket is rotated about the fixed axis of the suspension bearings, but any static out of balance condition tends to be compensated at the beginning of rotation as permitted by the springs carrying the freely rotatable basket and the stop limits.

The operations of the motors and the control valves will be readily apparent and need not be further described. It may, however, be pointed out that the pelton wheel and the electric motor above described give a flexible drive and a smooth acceleration and deceleration of the basket motion, and that they remain always in operative relationship with the basket, so that the basket may be rotated in two directions at the same time, if desired, and each motion is independently controlled. Many other advantages will be readily apparent.

It will now be appreciated that various modifications may be made in these constructions within the scope of this invention. For example, the pendulum ball and socket support for the basket shown in Fig. 1 may be reversed so that the basket is mounted on a ball and socket joint located therebeneath. Suitable springs may be connected between the inverted slide block and the casing to hold the basket in an uppermost position during washing. The centrifugal and pendulum action serving to compensate for an out of balance condition would act substantially the same as above described. Similarly, the structure of Fig. 5 may be reversed to have the yokes and their bearing support arranged below the basket. Also, the fluid pressure drives may be employed to rotate either continuously or oscillatively a clothes basket which is mounted for rotation about two axes but where no compensation can be made for an out of balance condition. Such an arrangement will make a double axis basket machine capable of automatic control for the two rotative motions and the introduction and removal of the desired fluids. Other modifications and various substitutions of parts for those herein described will be readily suggested to one skilled in the art. Hence, the above disclosure is to be interpreted as describing the principles underlying my invention and my preferred embodiments thereof and not as imposing limitations on the appended claims.

I claim:

1. Laundry apparatus comprising a container for cleansing fluid, a clothes basket therein, bearings supporting the basket for rotation about two axes which are substantially horizontal and vertical, means for supplying fluid under pressure, two sets of pelton wheel vanes connected to the basket and associated jet devices for delivering said fluid under pressure to the vanes and rotating the basket about either of said axes, and control means for causing said fluid under pressure to operate said mechanisms selectively for rotating the basket about either of said axes.

2. Laundry apparatus comprising a container for cleansing fluid, means for introducing the fluid thereto, a clothes basket therein, bearing supports which provide for rotation of the basket about a substantially horizontal axis, means supporting the basket for rotation about a substan-

tially vertical axis, a power operated pump for supplying under pressure fluid derived from the bottom of said container, independent hydraulic devices connected to the container for selectively rotating it about either of the axes, valve mechanism for supplying said fluid under pressure selectively to either of said devices, and valve mechanism for withdrawing fluid to a level below the basket which leaves fluid in the container for circulation by said pump, whereby clothes may be first cleansed while rotated in the fluid about a substantially horizontal axis and thereafter centrifuged by rotation above the fluid level about a substantially vertical axis.

15 3. Laundry apparatus comprising a container for cleansing fluid, a clothes basket therein, means supporting the basket for rotation about a substantially vertical axis and for universal lateral movement of the center of mass of the loaded basket towards alignment with said axis and the attainment of a running balance for an unequally distributed mass of clothes during rapid rotation thereof, mechanism for rotating the basket rapidly about said axis irrespective of any lateral 20 movement thereof, and means for imparting rotative motion to the basket about a different axis for cleansing the clothes by said fluid.

4. Laundry apparatus comprising a container for cleansing fluid, a clothes basket therein, 30 means supporting the basket for rotation about a substantially vertical axis and for a universal lateral movement of the center of mass of the basket towards alignment with said axis when the basket is rotated rapidly while loaded with an unequally distributed mass of clothes, a pivotal support for rotation of the basket about a different axis, and power mechanisms maintained in operative relationship with the basket for selective rotative movement of the basket about said 35 axes irrespective of the position of the basket when said movement is initiated.

5. Laundry apparatus comprising a fluid container, a clothes basket therein, a pivotal support for free rotation of the basket about a substantially horizontal axis, a pivotal support for rotation of the basket about a substantially vertical axis, means cooperating with said supports which provides for universal lateral movement 45 towards the vertical axis of the center of mass of the basket when loaded with unequally distributed clothes, means for removing the fluid from the container, means for rotating the basket rapidly about said vertical axis irrespective of said lateral movement, means for imparting slow 50 rotative movement to the basket about the horizontal axis and which leaves the basket free for rotation about the horizontal axis during rapid rotation about the vertical axis and automatically acting means for preventing free rotation of the basket about the horizontal axis during its high speed rotation about the vertical axis.

6. Laundry apparatus comprising a fluid container, a clothes basket therein, a pivotal support for rotation of the basket about a substantially vertical axis, a gimbal ring carried by said support, a pivotal support mounted on the ring for free rotation of the basket about a substantially horizontal axis and for universal lateral movement relative to the vertical axis, means for rotating the basket rapidly about said vertical axis, means for imparting slow rotative movement to the basket relative to the horizontal axis and a brake movably mounted on the gimbal ring for 65 engaging the basket which is biased out of con-

tact therewith and a pivotally mounted weight carried by the ring and operated by centrifugal force during rapid rotation of the gimbal ring which is connected to hold the brake in engagement with the basket, so that the basket is prevented from rotation about the horizontal axis during its rapid rotation about the vertical axis.

7. Laundry apparatus comprising a container for cleansing fluid, a clothes basket therein, means which supports the basket for rotative movement about one axis for the cleansing operation, a support for the basket which provides for rotating the same about a different and substantially vertical axis for a centrifuge operation, means cooperating with said supports which provides for universal lateral movement towards the vertical axis of the center of mass of the basket when loaded with unequally distributed clothes, power mechanism for rotating the basket rapidly about the vertical axis during its balance compensating movement, mechanism for imparting a slow rotative movement to the basket relative to the other axis, and means which limits the extent of said lateral movement during the rapid rotation.

8. Laundry apparatus comprising a container for cleansing fluid, a clothes basket therein, a support which provides for rotative movement of the basket about a substantially horizontal axis for the cleansing operation, a support which provides for rotation of the basket about a substantially vertical axis, means cooperating with said supports which provides for a universal lateral movement of the center of mass of the basket when loaded with unequally distributed clothes towards alignment with said vertical axis, separate independently controlled fluid pressure mechanisms maintained in operative association with the basket for rotative movement of the basket about the horizontal axis and a rapid centrifuge rotation about the vertical axis, means for supplying fluid under pressure and control means which causes the fluid under pressure to operate said mechanisms selectively for rotating the basket about either axis.

9. Laundry apparatus comprising a container for cleansing fluid, a clothes basket therein, means supporting the basket for rotation about a substantially horizontal axis, means supporting the basket for rotation about a substantially vertical axis, means cooperating with said supports which provides for lateral movement towards alignment with the vertical axis of the center of mass of the basket when loaded with unequally distributed clothes, power mechanism for selectively imparting rotative movement to the basket relative to each of its axes, means for introducing fluid to and removing it from the container for a washing operation, and means for introducing fluid under pressure directly into the interior of the basket for any position of rotation and lateral movement thereof, and which does not interfere with movement of the clothes.

10. Laundry apparatus comprising a container for cleansing fluid, a vertical axis rotatable support carried by the container, opposed yoke arms revolvably carried by the support and having diametrically opposite pivots, a gimbal ring pivoted on said pivots, a closable basket for clothes pivoted on the ring at right angles to the yoke pivots, means for introducing fluid to and removing it from the container, means for rotating the basket slowly within the gimbal ring, and means for revolving the yoke arms rapidly about the vertical axis and centrifuging the clothes.

11. Laundry apparatus comprising a fluid container, a clothes basket therein, a pivotal support for rotation of the basket about a substantially vertical axis, a second pivotal support providing for rotation of the basket about a substantially horizontal axis, means cooperating with said second pivotal support which provides for universal lateral movement towards alignment with said vertical axis of the center of mass of the basket when it is loaded with an unequally distributed mass of clothes, means for rotating the basket rapidly about the vertical axis irrespective of any lateral movement thereof, and means providing for a slow rotative movement of the basket about the horizontal axis.

12. Laundry apparatus comprising a container for cleansing fluid, a clothes basket therein, a support for rotation of the basket about a substantially vertical axis, a support for rotative movement of the basket about a substantially horizontal axis, means cooperating with said supports which provides for a universal lateral movement of the center of mass of a rapidly rotated unbalanced basket, means for delivering the container fluid under pressure, mechanism operated by said fluid pressure for rotating the basket about the horizontal axis, mechanism for rotating the basket about the vertical axis for any lateral position thereof and means for selectively causing the rotation of the basket by either one of said mechanisms.

13. Laundry apparatus comprising a container for cleansing fluid, means for introducing fluid thereto and removing it therefrom, a clothes basket, a first support for rotation of the basket about a substantially vertical axis, means including a second support carried by the first which provides for rotation of the basket about a substantially horizontal axis and universal lateral movement of the center of mass towards alignment with the vertical axis, mechanism for supplying fluid under pressure, fluid pressure operated vanes connected to the basket and associated jet devices for rotating the basket about both axes irrespective of said lateral movement, and means for selectively supplying fluid under pressure to cause either of said devices to rotate the basket.

14. Laundry apparatus comprising a container for cleansing fluid, a clothes basket therein, means for supplying fluid to the container to a level above the bottom of the basket, supports which provide for rotation of the basket about substantially vertical and horizontal axes, said container providing a fluid space beneath the basket, means for withdrawing the fluid from said space and supplying it under pressure, a device operated by said fluid under pressure for rotating the basket about the vertical axis, means including a valve controlled outlet for withdrawing fluid to a level below the basket which leaves a fluid supply in said space for operation of said device to rotate the basket about the vertical axis, and means for rotating the basket slowly about the horizontal axis while the valved outlet is closed and the level of the fluid is above the bottom of the basket.

15. Laundry apparatus according to claim 14 comprising means associated with the basket supports which provides for universal lateral movement towards alignment with the vertical axis of the center of mass of a rapidly rotated unbalanced basket having the clothes in an uneven

2,559,703

21

distribution, and the fluid pressure device is maintained in operative relationship with the basket for any position of lateral movement thereof.
